UNITED STATES PATENT OFFICE.

FREDERICK W. TURNER, OF ST. ALBANS, ENGLAND.

GAS-ENGINE.

SPECIFICATION forming part of Letters Patent No. 289,362, dated November 27, 1883.

Application filed November 10, 1882. (No model.) Patented in England March 29, 1879, No. 1,270, August 3, 1880, No. 3,182, and January 24, 1882, No. 362; in France September 29, 1879, No. 132,936, and July 22, 1882, No. 150,255; in Austria-Hungary March 1, 1880, No. 41,165 and No. 329, and February 19, 1881, No. 474 and No. 5,450; in Germany December 4, 1880, No. 11,093; in Belgium January 13, 1881, No. 53,566, and in Italy March 31, 1881, XV, 12,533, XXV, 93.

To all whom it may concern:

Be it known that I, FREDERICK WILLIAM TURNER, of St. Albans, England, engineer, have invented new and useful Improvements 5 in Gas-Engines, (for which I have obtained patents in Great Britain, No. 1,270, dated March 29, 1879, No. 3,182, dated August 3, 1880, and No. 362, dated January 24, 1882; a patent in France, No. 132,936, dated September 29, 1879; 10 a patent in Austria-Hungary, dated February 19, 1881; a patent in Italy, dated March 31, 1881; a patent in Belgium, No. 53,566, dated January 31, 1881, and a patent in Germany, No. 14,093, dated December 4, 1880,) of 15 which the following is a specification, reference being had to the accompanying drawings.

My invention relates to gas engines or motors—that is to say, engines worked by the explosive and expansive force of a mixture of 20 gas and atmospheric air during and subsequent to combustion.

Engines worked by the explosive and expansive force of a mixture of gas and air previously compressed to a pressure considerably 25 above that of the atmosphere have heretofore been constructed in such a manner that the force is applied to the crank-shaft during less than one-half of the revolution of the said shaft, the gaseous fluid being allowed to escape before its whole force is utilized, and in such engines the ignition of the gases, and consequent development of the greatest expansive force, takes place when the crank is on the "dead-point," or nearly so, and before the said 30 crank reaches that part of its course or path where the pressure acts most favorably for its propulsion. The pressure is considerably reduced in consequence of the condensation due to the expansion of the gases in the cylinder. 35 This action causes a fluctuating or irregular motion of the crank-shaft, which is very disadvantageous when the engine is required to drive machinery for electric lighting and similar purposes, where almost perfect uniformity 40 or regularity of speed is required, and it also results in a loss of power. Moreover, in these engines, as heretofore constructed, the cylinder

is elongated to provide space for the compressed gaseous charge, and in consequence of the piston not traversing this elongation, the 50 foul gases or products of combustion are not wholly expelled from the cylinder, a portion of them remaining within the said space and mixing with the succeeding charge of gas and air. This renders ignition difficult and uncertain, and weakens the succeeding explosive force. According to my present invention I obviate these difficulties in the manner herein-after set forth.

My invention has for its object to obtain 60 more uniform motion, first, in motors using compressed charges, by a more equable distribution of the explosive and expansive force to the crank-shaft of such motors, and by the expulsion of the foul gases from the cylinders. 65

My invention also has for its object to provide a novel method of attaching the slide-valve back plate to the cylinder.

My invention is illustrated in the accompanying drawings, in which Figure 1 represents 70 a side elevation, partly in section, of my improved gas-engine, with some of the parts removed. Fig. 2 represents a front elevation thereof, partly in section. Fig. 3 represents the gearing for operating the admission and 75 exhaust valves. Fig. 4 is a section of the slide-valve and slide-face on the line *xx*, Fig. 5, and Fig. 6 is an elevation of the slide-face and valve-chest. Fig. 6 is a plan of the slide valve, part of the cylinder, and the friction-plates, partly 80 in section. Fig. 7 is a front view of one of the friction-plates fastened to the sides of the valve-chest.

Like letters indicate the same parts throughout the drawings.

In Figs. 1, 2, and 3, A A' represent the cylinders; B B', the pistons, which may be connected in any suitable manner to the cranks C C', formed or fixed on the crank-shaft D nearly at right angles to each other. At the 90 upper end these cylinders communicate with one another by the port or passage E, in which is placed a conical valve, F. G is the slide-valve, which is operated by means of the con-

necting-rod G' and the crank H, fixed on the shaft I. This shaft is rotated in bearings in the frame of the engine and in the bracket J by means of the pinion K, fixed on the crank- 5 shaft D and gearing with the toothed wheel L, fixed on the shaft I. The cams M N are also fixed on this shaft. The cam M operates the valve F by means of the lever a, fixed on the shaft b, carried in the bearing c, which 10 is secured to the frame. On the other end of this shaft is fixed the lever a', to the end of which is coupled the connecting-rod d. This connecting-rod is also coupled to the lever e, pivoted at e', the other end of which enters a 15 slot in the stem of the valve F. The cam N operates the exhaust-valve O against the pressure of the spring O' by means of the lever f, pivoted at g, and having a short arm, f', connected to the rod h, which operates on the 20 spindle of the said valve at x. P is a valve for the admission of air, held to its seat by the spring P'.

When the engine is in operation and the parts are in the position shown in the drawings—that is to say, the piston B having performed nearly half of its downward stroke and the piston B' being at the top of its stroke—the cylinder A, above the piston B, contains gas and air, which have been admitted by the 25 opening of the valves G and P. The valve G is about to rise for the further admission of gas from the supply-aperture i through the port k. The valve F is also about to be opened by means of the cam M. When the piston B has reached the end of its downward stroke, the cylinder A is filled and the cylinder A' is 30 half filled with the charge of gas and air. During the upstroke of the piston B the whole of the charge is compressed into the 35 cylinder A. By the further movement of the engine in the same direction the charge is compressed from the cylinder A' into the cylinder A, and the pistons again arrive at the position shown in the drawings, one revolution of the crank-shaft having been completed. By 40 this time the valve G has moved downward to allow the charge to be ignited by the flame through the port t, and the valve F being open, the explosive force of the charge is exerted simultaneously upon the two pistons. The expansive force acts upon both pistons until the piston B' has nearly terminated its downward stroke, when the valve O is opened by means of the cam N, and the foul gases or 45 products of combustion are exhausted or expelled from both cylinders until the piston B terminates its upward stroke, when the valve F is closed to prevent the foul gases in the cylinder A' from entering the cylinder A, 50 while the piston B is performing the first half of its downward stroke and drawing in the fresh charge. During this movement the piston B' expels the foul gases from the cylinder A', and when the said piston arrives at the 55 top of its stroke the valve F is again opened to admit the gas and air into the cylinder A'.

It will thus be seen that the explosive force of the gaseous charge is exerted on both pistons, and during the downward movement of the pistons its expansive force is exerted simultaneously in both cylinders, which are in communication through the port or passage E. The expansive force drives or propels the piston B in the cylinder A during one-half of its downward stroke and drives or propels the piston B' of the cylinder A' during the whole of its downward stroke, less the requisite lead of the exhaust. Therefore the initial or explosive force is exerted upon the crank-shaft D by the piston B operating on the crank C, 80 and the subsequent expansive force by piston B' operating on crank C' practically through one-half of its entire revolution.

The parts of the engine are arranged to operate so that the crank C moves in advance of 85 the crank C', and at the time of ignition the crank C is at an angle with the axial line of the cylinder A, as shown in Fig. 1, the piston B having then performed nearly half of its outward stroke—that is to say, the crank C at the 90 instant of ignition and development of explosive force of the charge is in a position to utilize entirely such force, while the crank C' receives the explosive force at the same instant when on its dead-point. The arrangement of the cranks as above described insures the explosive force of the charge being utilized for driving the engine in the right direction when starting it, instead of retarding it, as is sometimes the case in engines heretofore 95 constructed when the ignition takes place prematurely.

The single slide-valve G serves for the ignition of the charge of gas and for regulating the admission of gas to the cylinder A; or the 100 gas may enter with the air through valve-passage P' by perforating the seat of the said valve. The pistons B B' are caused to work as close as practicable to the closed ends of the cylinders, so that the foul gases or products 105 of combustion are, as far as possible, expelled from both cylinders previous to the admission of a fresh charge of gas and air. Moreover, by the movement of the piston B in advance of the piston B', a space is afforded in the cylinder A for the compressed charge of gas and air prior to ignition, thus obviating the necessity for an elongation of the cylinder for this purpose, as heretofore employed. In 110 every alternate revolution each cylinder acts 115 as a charging and compressing pump to the other—that is to say, during a portion of the revolution of the crank-shaft the piston partly compresses the charge into the cylinder A', while during another part of the revolution 120 of the said shaft the piston B' compresses the charge into the cylinder A, when it is ignited. This alternate compressing action of the pistons thoroughly mixes the gaseous charge as 125 required previous to the ignition of the same.

I attach the slide-valve back plate to the cylinder in the following manner—that is to say,

to the sides of the valve-box in which the slide-valve works I fix by screws s two flexible plates, r , of steel or other metal. These extend to the outsides of the back plate, to which they are attached also by screws; but the holes in the said plates, through which these screws pass, are elongated sufficiently to allow an outward movement of the back plate equal to the extent of expansion of the valve when it becomes heated. The friction of the flexible plates upon the sides of the back plate caused by the pressure of the aforesaid screws is intended, partially, to provide the resistance necessary for holding the back plate in position against the explosive and expansive force of the gases in the cylinders, thereby rendering unnecessary the very heavy pressure exerted by strong springs t' on the back plate, so that comparatively weaker springs can be used for the regulation of the pressure. Moreover, the pressure on the valves and liability to abrasion will be materially reduced.

What I claim is—

1. In a gas-motor having two cylinders, pistons, and cranks, the combination, with said cylinders, of a passage connecting them, a valve whereby said passage is opened and closed, and air and gas ports which are opened to admit the charge into one cylinder when the

piston has partly completed its stroke, the other piston having finished its movement at the same instant, and suitable devices for operating the valve between the two cylinders, so that the charge may be compressed from one into the other and the expansive force exerted upon both simultaneously, said valve being closed after the explosion to prevent admission of foul vapors into the cylinder receiving the charge, substantially as described.

2. The combination, with the two cylinders connected by the passage E , having valve F , of the air and gas ports, arranged as described, and pistons moving in said cylinders, one in advance of the other, the valve F being adapted to open before the explosion and to close afterward, substantially as described.

3. The slide-valve back plate attached to the sides of the valve-chest by means of flexible plates and screws, to allow an outward movement of the said back plate equal to the extent of the expansion of the valve when it becomes heated, and to afford the necessary resistance for holding the said back plate in position, substantially as set forth.

F. W. TURNER.
